UNITED STATES PATENT OFFICE.

LEO F. ADT, OF ALBANY, NEW YORK.

EYEGLASS-GUARD.

1,239,245.

Specification of Letters Patent.

Patented Sept. 4, 1917.

Original application filed December 30, 1909, Serial No. 535,543. Patent No. 1,103,240, dated July 14, 1914. Divided and this application filed July 13, 1912. Serial No. 709,208.

To all whom it may concern:

Be it known that I, LEO F. ADT, of Albany, in the county of Albany and State of New York, have invented certain new and useful Improvements in Eyeglass-Guards; and I do hereby declare the following to be a full, clear, and exact description of the same, reference being had to the accompanying drawings, forming a part of this specification, and to the reference-numerals marked thereon.

My present invention relates to eyeglasses, and it has for its object to provide a simple, neat and convenient eyeglass guard such as constitutes the gripping portion that engages the nose of the wearer to hold the eyeglasses in place. Further objects of my invention are to provide a guard that can be cheaply manufactured but will be capable of being easily adjusted in all of the ways required to render the guard universally applicable to the noses of different wearers having different facial characteristics. To these and other ends the invention consists in certain improvements and combinations of parts all as will be herein-after more fully described, the novel features being pointed out in the claims at the end of the specification.

30 In the drawings:

Figure 1 is a top plan view of an eyeglass mounting provided with a nose guard constructed in accordance with and illustrating one embodiment of my invention;

35 Fig. 2 is a bottom plan view of the same mounting;

Fig. 3 is a transverse, central, vertical section through the eyeglass bridge showing one of the guards in side elevation, and

40 Fig. 4 is a detail view of one of the guards detached showing the latter in elevation from the opposite side.

Similar reference numerals throughout the several figures indicate the same parts.

45 My improved guard is applicable to the finger piece type of mounting and in the present instance I have illustrated it in connection with such a construction, being that also shown and described in my prior application for patent on eyeglass mountings, filed December 30, 1909, Serial No. 535,543, of which application this application is a division.

50 Referring therefore only generally to the mounting as a whole it may comprise the

usual rigid bridging portion 1 having lens attaching portions 2 at the ends thereof and pliable loops or portions 3 connecting each end of the bridge with its respective lens attaching portion for purposes of pupillary adjustment. Headed pivot pins 4 are carried at each side by brackets 5 which project outwardly from the ends of the bridge into the loops or pliable portions and on these pivots swing the nose guards. 60 65

Each guard, in the present embodiment, is formed from a single piece of flat stock that embodies a lever portion 6 provided at its forward end with an outwardly extending finger piece 7 preferably connected thereto by a downward or vertical bend 8 and also provided at its rear end with a forwardly opening adjustable loop 9 formed by bends transversely of the flat faces of the stock and connected to the upper edge of an 70 75 outwardly extending arm 10 which, in turn, is connected by a horizontal bend 11 with the forward portion or edge of the nose engaging member 12 preferably having upper and lower nose engaging surfaces 13 and 14. 80

It will be noted that the loop 9 is vertically arranged below the upper surface of the lever 6 so that said loop is hidden by the connecting portion 3 of the mounting. This loop 9 permits the nose engaging member to 85 be raised or lowered or to be moved in or out, and further, to be moved forward or backward to agree with the facial characteristics of the wearer, said movements being effected with pliers or otherwise in a manner well known by skilled opticians. The nose 90

engaging member may also be tilted to conform to the forward taper of the nose, this being accomplished by adjusting the same about the bend 11 as an axis. Each guard 95

turns above the general support offered by the bridge and connecting parts of the mounting upon its bearing or pivot 4 in accordance with the usual mode of operation of finger piece eyeglasses, the lever 6 being 100 provided in one edge with a laterally opening bearing recess 15 permitting the guards to be attached to or separated from the mounting by a lateral movement, and in order to strengthen the lever in proximity 105 to the recess, the opposite edge thereof is preferably bent upwardly to provide a longitudinally extending flange 16 opposite said recess, as clearly shown in Figs. 1 and 4.

The springs for positioning the guards in 110

the particular embodiment illustrated, are located upon the under side of the support and comprise in each instance an offset coil 17 supported by one extremity in a tube or 5 securing device 18 on the mounting beneath the bracket 5 while the other end extends to the other side of the pivot of the guard that the spring operates and engages one arm of the guard lever as at 19.

10 Of course, it is to be understood that my improved guard is not limited in its use to eyeglasses of the finger piece type, though it is particularly adapted for such use inasmuch as it can be blanked out in one piece 15 from the sheet of material used for the pivoted guard lever, including its finger piece. The disposal of the flat bend 9—10—11 constituting the connection of the upper and lower pads 13 and 14 with the supporting 20 arm is simple of formation and the disposal of the parts is such that provision is made for every one of the ordinary adjustments that the optician is called upon to make including upward and downward bodily 25 displacement as by compressing or expanding the loop 9; upward and downward tilting by distortion of this loop laterally; forward or rearward spacing by similar distortion of the loop 9 or more preferably by adjustment 30 at the bend 11 and also inward or outward setting of the nose engaging portions by lateral distortion of the loop 9 to cause the pads to grip the nose to a greater or less degree with a given throw of the guard lever, 35 or generally to fit noses of greater or less breadth. With all this, and particularly in a finger piece mounting, the means which permit these adaptations are so arranged that they are inconspicuous with the mounting in normal position upon the nose of the 40 wearer.

I claim as my invention:

1. A nose guard for eyeglasses embodying a supporting arm formed into a forwardly 45 opening adjustable loop having one end connected to an outwardly extending member at the front edge of the nose pad.
2. A nose guard for eyeglasses comprising a nose engaging pad having an arm proceeding outwardly from the forward edge 50

Copies of this patent may be obtained for five cents each, by addressing the "Commissioner of Patents
Washington, D. C."

thereof, thence rearwardly, thence forwardly substantially parallel to the rearwardly extending portion to form a forwardly opening adjustable loop.

3. A nose guard formed of flat stock embodying a lever having a finger piece at its forward end, a vertically arranged loop at its rear end located substantially in the vertical plane of the lever formed by bends flatwise of the stock, and a nose bearing member having an outwardly extending arm connected to the edge thereof by a bend, said arm being an integral continuation of the loop and a part of a uniformly distortable length of stock comprising the lever, the two arms of the loop, and the said nose bearing arm.

4. A nose guard embodying an integral structure comprising a rearwardly extending supporting arm and upper and lower nose bearing pads, the pads being connected to the arm by a forwardly opening vertically disposed adjustable loop and to each other independently of the arm.

5. A nose guard comprising a nose-engaging member embodying upper and lower nose bearing pads, a lever formed of flat stock having its flat faces horizontally arranged, its forward end provided with a finger piece and a bearing between its ends, and an adjustable and vertically arranged loop connecting the nose engaging member and the lever and located rearwardly of the forward edge of the former, said loop being formed in one piece with the lever, and the bearing pads being connected to each other independently of the said loop.

6. In an eyeglass mounting, the combination with a support, of an operating arm pivotally mounted upon said support intermediate its length and provided in the rear of the support with a loop with the plane thereof in the direction of the length of the arm and with its terminal extended transversely to the plane of the loop.
